UNITED STATES PATENT OFFICE

ABRAHAM L. BUSCHMAN, OF NEW YORK, N. Y.

DESIGN FOR A COMBINED CHRISTMAS TREE LIGHTING SET AND DISPLAY RECEPTACLE THEREFOR OR THE LIKE ARTICLE

Application filed May 26, 1931. Serial No. 39,972. Term of patent 7 years.

To all whom it may concern:

Be it known that ABRAHAM L. BUSCHMAN, a citizen of the United States and resident of New York city, in the county of New York and State of New York, has invented a new, original, and ornamental Design for a Combined Christmas Tree Lighting Set and Display Receptacle Therefor or the Like Article, of which the following is a specification, reference being had to the accompanying drawings forming part thereof, in which—

Fig. 1 is a front perspective view of a

combined Christmas tree lighting set and display receptacle therefor, embodying my new design; and

Fig. 2 is a cross-sectional view taken on line 2—2 of Fig. 1.

I claim:

The ornamental design for a combined Christmas tree lighting set and display receptacle therefor or the like article, substantially as shown.

Dated May 22, 1931.

ABRAHAM L. BUSCHMAN.
